UNITED STATES PATENT OFFICE.

JOSEPH FERRANDO, OF GENOA, ITALY.

STEAM-BOILER.

SPECIFICATION forming part of Letters Patent No. 324,545, dated August 18, 1885.

Application filed May 8, 1885. (No model.) Patented in Italy April 21, 1883, No. 15,355, July 5, 1883, No. 15,617, February 7, 1884, No. 16,366, and December 22, 1884, No. 17,599; in England August 18, 1883, No. 4,013, and June 6, 1884, No. 8,681; in France November 14, 1883, No. 156,877; in Belgium November 15, 1883, No. 63,079, and February 29, 1884, No. 64,184; in Germany March 11, 1884, No. 26,259; in Austria-Hungary April 18, 1884, No. 46,698 and No. 16,472, and October 31, 1884, No. 21,621 and No. 50,684, and in Spain June 13, 1884, No. 3,929.

To all whom it may concern:

Be it known that I, JOSEPH FERRANDO, of Genoa, Italy, have invented certain new and useful Improvements in Steam-Boilers, of which the following is a full, clear, and exact description.

This invention relates to certain new and useful improvements in that class of fire-places burning pulverized or granulated fuel; and to the object of my invention is to construct the fire-place in such a manner that the pulverized fuel is not drawn rapidly to the rear end of the fire-place before it is fully consumed.

Reference is to be had to the accompanying drawings, forming part of this specification, in which similar letters of reference indicate corresponding parts in all the figures.

Figure 1 is a front view of a boiler provided with my improved fire-place. Fig. 2 is a longitudinal sectional elevation of the same on a smaller scale. Fig. 3 is an enlarged cross-sectional view of a fire-place tube.

The fire-place is constructed with two or more half tubes or boxes, A, closed at the bottom and open at the top, and extending from the front plate, C, of the boiler D to the fire-wall E, and on the top edges of the sides of the tubes A the grate-bars F are placed transversely, the grate-bars being placed very close, so that the pulverized or granulated fuel cannot fall down between them. The front ends of the half-tubes A are connected by a closed box, I, open at one end to admit the compressed air. The half-tubes A form the ash-pits. The air admitted to the fire can

only pass through the box I and the half-tubes A. As the grate-tubes are placed very closely, they become heated to a very high degree and must be cooled. This is accomplished by conducting steam from the dome 40 into the fire-place half-tubes, through the pipe H and by conducting liquids or gases or gases and liquids into half-tubes through tubes K, which are perforated and located under the grate-bars.

45 M are the fire-place doors.

Having thus described my invention, what I claim as new, and desire to secure by Letters Patent, is—

1. The combination, with one or more boiler-furnaces, of the fire-boxes, upon which the grates are supported, and a fire-wall, the fire-boxes extending from the front of the furnace to the said fire-wall, substantially as herein shown and described.

50 2. The combination, with a boiler-furnace, of the fire-boxes, upon which the grates are supported, a fire-wall, to which fire-wall the fire-boxes extend, and of an air box connected with the front ends of the fire-boxes, which air-box is outside of the front end of the boiler, substantially as herein shown and des r

55 The foregoing specification of my improvement in fire-grates burning fine and dusty fuels signed by me this seventh day of April, 1885.

JOSEPH FERRANDO.
